(57) **CLAIM**

The ornamental design for a shoe, as shown and described.

DESCRIPTION

FIG. 1 is a lateral, rear perspective view of a shoe showing my new design;

FIG. 2 is a lateral side elevational view thereof;

FIG. 3 is a medial side elevational view thereof;

FIG. 4 is a top plan view thereof;

FIG. 5 is a front elevational view thereof.

FIG. 6 is a rear elevational view thereof; and,

FIG. 7 is a bottom plan view thereof.

The broken lines in FIGS. 1-7 and areas within the broken lines represent portions of the shoe that form no part of the claimed design.

1 Claim, 3 Drawing Sheets
